UNITED STATES PATENT OFFICE

2,675,611

ONE ARM CAN OPENER

Walter E. Moore, St. Louis County, Mo., assignor
to Swing-A-Way Manufacturing Company, St.
Louis, Mo., a corporation of Missouri

Application May 19, 1952, Serial No. 288,646

10 Claims. (Cl. 30—9)

1

The present invention pertains generally to domestic appliances, and more particularly to an improved can opener of the leverless wall type in which the can top is severed from the can body by a crank driven rotatable disc cutter operating in conjunction with a driven feed wheel which supports and rotates the can.

In brief, the present novel single actuator can opener includes a driven feed wheel mounted on a support on a fixed axis. Cooperating with said feed wheel and mounted on said support is a shiftable driven rotatable cutter, gears interconnecting the two when in can severing relation. A crank arm is mounted on the axis of the feed wheel for positively driving the latter, to which is secured a cam for shifting the cutter sequentially into can piercing and can severing positions when the crank arm is rotated forwardly. Further, a dog spring biased into one position is pivotally mounted on a hub of the crank arm for rotary movement therewith which shifts the cutter to inoperative position when the crank arm is rotated backwardly. No positive locking means is provided to maintain the cutter in can severing position during the lid, or the like, removal operation, the resistance of the metal to severance by the cutter effectively maintaining the cutter in can severing position. The shifting of the cutter to inoperative position is assisted by the frictional engagement of the can edge between the cutter and feed wheel, although the dog effects positive shifting once it is engaged.

A primary object of this invention is to provide a novel wall can opener of the leverless type wherein all of the movable mechanism for piercing, cutting, rotating, and releasing a can is operable by the rotation of a single crank arm.

A further object is to provide a novel can opener of the leverless type which incorporates mechanism for simultaneously positively rotating and severing a can which is sequentially actuated and released by rotation of a single crank arm first in one direction and then in the other.

Another object is to provide a novel can opener of the leverless type having a cutter which may be brought into can top piercing and severing position by the proper continuous directional rotation of a single crank arm, and in which the cutter is maintained in can severing position as the severing progresses by resistance to severance of the metal.

A distinctive feature of the invention resides in the absence of any lever or other contrivance to be manipulated either before, during, or after

2

a lid severing operation, a single crank arm, provided with a knob, being the only element requiring manipulation, so that little skill is required on the part of the operator. In other words, after a can has been positioned, all of the objectives of the invention are attainable by rotating the single crank arm first in one direction to pierce and sever metal, and then in the opposite direction to release, as will appear.

10 The foregoing and other objects, features and advantages of the invention will be apparent or pointed out in the description to follow, reference being had also to the accompanying drawings, wherein:

15 Fig. 1 is an elevational view of a can opener incorporating the teachings of the present invention, the view portraying the feed wheel side of the opener with the device in can-receiving position;

20 Fig. 2 is an elevational view of the opener portraying the opposite side thereof;

Fig. 3 is a vertical sectional view taken on the lines 3—3 of Figs. 1 and 2;

25 Fig. 4 is a fragmentary view, similar to Fig. 1 with the device in can top piercing position;

Fig. 5 is a fragmentary view of the opposite side of the opener in a position corresponding to that of Fig. 4;

Fig. 6 is a top plan view of Fig. 4;

30 Fig. 7 is an enlarged scale vertical sectional view taken on the line 7—7 of Fig. 1, with a can, shown fragmentarily in vertical section, being in position for having its top pierced and severed;

Fig. 8 is a view similar to Fig. 7, but taken on the line 8—8 of Fig. 4, and showing a can top piercing operation;

Fig. 9 is an enlarged scale elevational view, partly in section, and taken on the lines 9—9 of Figs. 6 and 8;

40 Figs. 10 and 11 are views similar to Fig. 9, illustrating the successive positions of certain elements during a can top severing cycle;

Fig. 12 is an enlarged scale vertical sectional view on the line 12—12 of Fig. 1;

45 Fig. 13 is a fragmentary elevational view of the body portion of the crank arm;

Fig. 14 is a view of an included carrier member;

Fig. 15 is a horizontal sectional view on the line 15—15 of Fig. 14;

Fig. 16 is a view of the main frame, or base plate of the opener whereon the operating mechanism is mounted;

Fig. 17 is a horizontal sectional view on the irregular line 17—17 of Fig. 16;

Fig. 18 is a top plan view of an actuator; Fig. 19 is a perspective view of a link element; Fig. 20 is a face view of a cam; and Fig. 21 is a perspective view of a pawl-shaped dog element.

With particular reference now to Figs. 1 and 2, numeral 30 indicates, as a whole, a can opener constructed in accordance with the teachings of the instant invention. Generally, the can opener 30 includes: a main frame or base plate 32; suitable supporting means 34 rigid with one end thereof, for mounting the opener on a conventional wall bracket, not shown; a feed wheel assembly 36; a can top piercing and severing mechanism 38; a shiftable carrier or supporting member 40 for the latter mechanism; a crank arm assembly 42 for rotating the feed wheel and also for shifting said mechanism 38 and member 40; a cooperating spring biased dog and cam mechanism 44 incorporated in said crank assembly 42; a device 46 for stabilizing the can during a severing operation; and other embodied elements described more particularly hereinafter.

As seen to best advantage in Figs. 16 and 17, the base plate 32 is of elongated form, and has apertures 48 adjacent one end thereof for the reception of rivets 49 or the like, whereby the supporting bracket 34 is secured thereto. Adjacent the other end, the plate 32 has formed therein a laterally pressed circular boss portion 50 having therein an irregular opening 52. The latter includes a first semi-circular section 54, and a pair of similar sections 56 and 58 joined by an arcuate section 60, as shown.

The plate 32 has also formed therein a laterally pressed substantially oval boss portion 62 provided with an elongated angularly disposed slot 64. An integral bearing support sleeve 66 is formed in the plate, and a horizontally disposed can engaging integral flange 68 projects from the lower marginal edge of said plate 32.

The assembly 36 includes a flat faced feed wheel 70, having a serrated peripheral edge 72, and rigidly attached to one end of a rotary shaft 74 which is supported in the bearing support sleeve 66 of the plate 32; and a pinion 76 also rigid with said shaft 74, as clearly shown in Figs. 7 and 8.

The can top piercing and severing mechanism 38 is rotatably angularly mounted on the carrier 40, the configuration of which is illustrated particularly in Figs. 14 and 15. The carrier 40 comprises a generally flat body portion 78, provided approximately centrally thereof with an oval shaped bulge portion 80, and has a horizontal can brim engaging flange 82 projecting therefrom, as shown. Openings 84 and 86 are provided in the body portion 78, and an opening 88 in the bulge portion 80.

With particular reference again to Figs. 7 and 8, the mechanism 38 includes a rotatable cutter disc 90 secured to one end of an inclined stud 92 by means of a nut 94, or otherwise. The stud 92 is headed as shown, is supported in the bulge opening 88, and rotatably supports a pinion 96 which is maintained in firm engagement with a flange 98 of the cutter disc, by means of a compression spring 100 interposed about said stud between the bulge 80 and said pinion 96. The carrier 40 is pivotally mounted at one end on a rivet 102 which extends through the slot 64, and which also serves as a pivot for one end of an actuated plate 104 shown in Fig. 18.

With reference particularly also to Figs. 2 and 5, the actuated plate 104 includes a flat body

portion 106 having a boss surrounded circular opening 108 adjacent one end, and a similar square opening 110 adjacent its other end. The aforesaid rivet 102 passes through opening 108, and the square opening 110 is adapted to receive a stud for supporting the device 46, as will appear. The body portion 106 of the actuator is recessed at 112, and carries a rigid horizontally projecting pin 114.

10 The crank assembly 42 comprises a crank including a cup-shaped upper end 118, and an arm 120 integral therewith. A knob 122 is mounted by means of a rivet 124 on the free extremity of said arm 120, and said upper end 118 includes an annular peripheral flange 126, and a centrally located irregularly contoured boss 128, the configuration of which appears especially in Fig. 13. It is noted that boss 128 is centrally bored at 129 to receive a bushing 130 through which the shaft 74 extends, a light compression spring 131 being interposed about a portion of said shaft between the end of said bushing 130, and the bottom of the bore 129. The end portion 132 of the shaft is knurled and peened over as shown in Figs. 7 and 8, so that, as should be manifest, shaft 74 and crank 116 always rotate in unison.

15 Integrally formed on the boss 128 is a pair of cylindrical projections or lugs 134, each adapted to enter one of the pair of circular openings 136 provided in a cam plate 138 which is included in the mechanism 44 (Fig. 20). A third cylindrical projection or lug 140 is also integral with boss 128, and is adapted to enter a third circular opening 142 in cam plate 138. It is noted that the face 20 of boss 128 in the region about lug 140 is undercut or recessed at 144 for a reason to appear. A notch or socket 146 is also provided in boss 128 for the reception of a block of neoprene 148, one end of which projects into the recess 144, as best 25 seen in Fig. 13.

30 The cam plate 138 referred to above is of the configuration illustrated in Fig. 20, where it is seen that its peripheral diameter gradually increases clockwise from an arcuate recess 150 in the plate, to the apex of a lobe 152 which partially defines said recess. The cam plate 138 also has an opening 154 therein of a size to accommodate the bushing 130 about which the plate 138 is eccentrically positioned, as the drawings show.

35 The mechanism 44 also includes a pawl-shaped dog member 156, the configuration of which is clearly shown in Fig. 21. The dog 156 has an opening 158 therein, and includes a tail piece 159, converging arcuate edges 160 and 162, and is provided with an aperture 164. Said dog is pivotally mounted via opening 158 on lug 140, between the face of recess 144 and the cam plate 138. Its arcuate edge 162 is normally biased outwardly into engagement with annular flange 126 of the crank 42 by means of a spiral spring 166 which encircles and is anchored at one end to the lug 140, and has its other end 168 anchored in aperture 164. A circular depression 170 in boss 128 about the lug 140 accommodates the spiral portion of spring 166.

40 With particular reference to Fig. 12, the device 46 is seen to be mounted on the projecting stem 172 of a headed stud 174, which also includes a squared section 176 fitting within the correspondingly contoured opening 110 of the actuator 104. Stem 172 also extends through a circular opening 178 of an oscillatory link 180 which, as shown in Fig. 19, has an 8-shaped peripheral outline. The lower half segment 182 of

Link 180 contains the opening 178. The upper half segment 184 is nonperforate, and has a snug fit within the semicircular section 54 of the irregular opening 52 in the base plate 32. In addition to stem 172, the device 46 includes a can stabilizing plate 186 which is mounted on said stem, between the carrier 40 and a cup-shaped compression spring retainer 188.

A relatively heavy compression spring 190 is interposed about stem 172 between the stabilizing plate 186 and retainer 188, and the latter is maintained in place by means of a C-washer 192 which engages a reduced neck 194 provided on said stem as clearly illustrated. As Figs. 1, 4 and 6 demonstrate, plate 186 has an integral abutment edge 196 which is adapted to engage the brim of the can in the operative position of the piercing and severing mechanism.

Operation

The inoperative position of the present opener 30 is illustrated in Figs. 1, 2 and 7. In such position, the piercing and severing mechanism 38 is in raised position, and the supporting carrier 40 for said mechanism is in what will be termed its forward position. That is to say, carrier 40 has been advanced or shifted angularly upwardly and outwardly away from support 34, by the final manipulation of the crank assembly 42 at the end of the cycle, as will be described.

It is to be observed as detailed, with specific reference to Figs. 3 and 12, that the carrier 40 and the actuated plate 104 are connected by means of the rivet 102 and the stud 174, so that the two are shifted in unison along opposite sides of the base plate 32. It is also to be observed that in this advanced position of the carrier-actuated plate, the transverse rivet 102 extends through inclined slot 64 at the uppermost end of the latter, and that the lower half segment 182 of link 180, mounted on stem 172 of the stud 174, is in engagement with the semicircular section 58 of the irregular opening 152 in the base plate 32.

Assuming now that it is desired to sever the top T from a can generally designated C, said can is brought into final position, with the depending circumferential edge of its bead B resting on the serrated edge 72 of the feed wheel, and its body wall W in contact with the flat face of said wheel, as illustrated in Fig. 7. It is also seen that the flange 68 of the base plate 32 serves to facilitate positioning of the can. At this time, the dog and cam mechanism 44 are in the inactive, or cycle completed stage portrayed by full lines in Fig. 11, with the actuator pin 114 nestled in the recess 150 of the cam plate 138, the dog 156 biased into contact with the flange 126 of the crank cup 118, and with the crank arm 120 hanging in a substantially perpendicular position.

With can C now in position, as in Fig. 7, crank 42 is rotated counterclockwise, as viewed in Figs. 1 and 11. During the initial revolution of the crank arm 120, the ever increasing peripheral diameter of the cam plate 138 forces the pin 114 from the Fig. 11 position thereof to the position it occupies in Fig. 9. In other words, at the end of the initial revolution of the crank arm, the cam lobe 152 has moved the pin 114, and with it the actuated plate 104 and carrier 40 rearwardly and angularly downwardly, so that the cutter disc 90 has penetrated the can top T, as portrayed in Fig. 8.

For a clearer understanding of the disposition

of the parts at such time, attention is also directed to Fig. 4. There it is seen that rivet 102 now extends through inclined slot 64 at the lowermost end of the latter, and that the lower half segment 182 of link 180 is in engagement with the semi-circular section 56 of the irregular opening 152 in the base plate 32. The movement of the carrier-actuator has also brought abutment flange 82 into firm engagement with the bead B along the top edge, and abutment flange 196 into yielding engagement with the periphery of said bead, so that penetration of the cutter disc has been facilitated, as is understood. As shown in Figs. 5 and 8, the recess 112 is provided in the actuated plate 104 in order to at all times clear the bearing support sleeve 66.

The movements and disposition of parts incident to the completion of the initial counterclockwise revolution of the crank arm 120 have now been described. Rotation of said crank arm 120 is continued in non-stop fashion until complete severance of top T has been accomplished.

The resistance to severance of the can metal by the cutter disc 90 effectively maintains the carrier 40 and the cutter 90 rearwardly in operative can severing position. No positive locking mechanism, such as is found in lever type and other leverless can openers, is required. This comprises an important feature of the present invention. Additionally, the release movement is initiated prior to engagement of the dog 156 by the frictional engagement of the cutter disc 90, the can C, and the feed wheel 70 as the crankarm 120 is reversed from cutting rotation. The utilization of these forces reduces wear on the parts, and aids in simplification.

Because of the biasing action of spring 166, the dog 156 would snap off of the pin 114 during each required revolution for lid severance, to thus create an audible click each time the extremity thereof would strike against annular flange 126, except for the block 148 of neoprene mounted in the recess 146 of the boss 128. As appears in broken lines in Fig. 9, the projecting end of said block yieldingly bears against the tail piece 150 of the dog 156, so that the biasing action of spring arm 168 is retarded sufficiently to eliminate clicking, as should be apparent.

Obviously, the number of counterclockwise revolutions required to sever a lid is dependent on the diameter of the can C. Thus, for example, should the can be of a size requiring about six and one quarter turns, the relative position of the crank and associated elements will be as illustrated in Fig. 10. Now the crank arm 120 is turned clockwise, with the arcuate edge 162 of the dog 156 sliding along the inner periphery of cup flange 126, until the arcuate edge 160 of said dog contacts the pin 114, as shown in Fig. 11 by broken lines. During the next few degrees of rotation, said dog forces the pin 114 to ride over the cam lobe 152 and into the recess 150 of the cam plate 138. As a result, the connected carrier 40 and actuated plate 104, and the mechanism mounted thereon, return to the Fig. 1 position thereof, so that removal of the now open can completes a cycle of operation.

It is to be observed that, when actuator pin 114 has been brought into the position illustrated in Fig. 11, no further clockwise rotation of the crank 120 is possible, because rivet 102 will have reached the upper end of inclined slot 64, and simultaneously the lower segment 182 of link

180 will have been brought into engagement with section 58 of the irregular opening 52.

From the foregoing, it should be manifest that the invention provides a can opener incorporating novel mechanism for the attainment of its objectives and advantages. It is to be understood that the precise details of construction illustrated and described have been given by way of example, rather than in a limiting sense. Therefore, the invention contemplates any modifications, or substitutions of equivalent elements, that may be had without departing from the scope of the appended claims.

What is claimed is:

1. A can opener including, in combination, a plate-like support, means secured to said support for mounting the same in a vertical plane, can top piercing and severing means mounted on said support for compound movement parallel thereto, a feed wheel mounted on said support for rotation in a plane parallel thereto, and a crank assembly for effecting both a compound movement of said can top piercing and severing means and rotation of said feed wheel, said compound movement being at least approximately tangential with respect to said feed wheel and in the direction of rotation thereof.

2. A can opener including, in combination, a plate-like support having spaced openings therein, a feed assembly mounted on said support, said feed assembly including a feed wheel mounted for rotation in a plane parallel to said plate-like support and crank means for rotating said feed wheel, can top piercing and severing means mounted on said support for bodily movement in a plane parallel to said plate-like support, said latter means including a cutting member and a carrier therefor, said carrier including transversely extending elements respectively received in said spaced openings in the plate-like support for guided movement therein, and means movable with said crank means for engaging and bodily moving said carrier along its path of guided movement during the first only of a series of revolutions of said crank means.

3. The combination of claim 2 wherein the carrier has a can engaging stabilizing device supported thereon for movement therewith.

4. The combination of claim 3 wherein the can engaging stabilizing device is yieldably mounted on the carrier.

5. The combination of claim 2 wherein at least one of the spaced openings in the plate-like support is a straight elongated slot restricting the transversely extending element received therein to movement in a straight line.

6. The combination of claim 2 wherein at least

one of the spaced openings in the plate-like support is of lobate shape, a link disposed in said one spaced opening for oscillating movement therein, and a pivotal connection between said link and said carrier.

7. In a can opener, the combination of a support, rotatable feed means mounted on the support, a cutting device, carrier means mounting the cutting device on the support for limited displacement relative thereto, said carrier means itself being bodily displaceable from a first position to a second position relative to the support, and actuating means mounted on the support and secured to said feed means for simultaneously rotating said feed means and bodily displacing said carrier means from said first position to said second position and for thereafter continuing to rotate said feed means without further displacement of said carrier means.

10 8. The combination of claim 7 wherein said actuating means includes means effective upon reversed rotation of said feed means to displace said carrier means from said second position to said first position.

15 9. The combination of claim 8 wherein the actuating means comprises cam means including yieldable dog means rotatable with said feed means, said cam means being adapted for driving engagement with the carrier means for displacement of the latter toward said second position, said dog means being adapted for driving engagement with the carrier means for displacement of the latter toward said first position.

20 10. The combination of claim 9 wherein the actuating means includes a cup-like portion having a peripheral wall for enclosing the cam means, the dog means being yieldably biased toward said peripheral wall, and a resilient cushion for retaining the dog means out of contact with said peripheral wall in the absence of driving engagement between the dog means and the carrier means.
